EX
DESIGN.

—O—
F. MANKEY.

MOLDING.

No. 16,956.

Patented Oct. 26, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,956, dated October 26, 1886.

Application filed July 1, 1886. Serial No. 206,808. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding in the form of a band or bar; and it consists in the configuration thereof, substantially as represented.

On each edge appear a series of regular scallops or convexities, A B. The scallops A on one edge are separated by intervals or spaces C. The scallops B on the other edge are separated by the intervals or spaces D. The scallops A are opposite the spaces D, and the scallops B are opposite the spaces C. On the face 20 of the bar are inwardly-curved depressions or

recesses E, beveled or inclined toward the edge intervals C and D.

The general appearance of my design is that of a sinuous band or elevation upon the face of the bar, the said sinuosity being outlined by the scallops A B and the recesses E. The said sinuous band, measured across the scallops, is wider than the straight bar, upon which it is apparently superimposed.

I claim—

The design for an ornamental trim or molding, substantially as herein shown and described, which consists in the scallops or convexities A B and intervals C D on opposite edges of the trim, and on the face thereof the 35 inwardly-curved recesses E.

FREDERICK MANKEY.
